[57] CLAIM

The ornamental design for a television receiving antenna, as shown and described.

DESCRIPTION

FIG. 1 is a front and right side perspective view of a television receiving antenna showing our new design, with the rods stretched;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof;

FIG. 8 is a front and right side perspective view of a second embodiment of the television receiving antenna illustrated in FIG. 1, with the rods stretched;

FIG. 9 is a front elevational view of the embodiment disclosed in FIG. 8; and

FIG. 10 is a top plan view of the embodiment disclosed in FIG. 8.
